CLAMP

Walter W. Carroll, Anderson, Ind.

Application October 11, 1948, Serial No. 53,781

1 Claim. (Cl. 90—59)

This invention relates to machine clamps for use in clamping the work or fixtures to the platen or table of a machine tool, such as a planer or milling machine. Such platens and tables are commonly provided with T-slots adapted to receive the heads of bolts which extend upwardly above the surface of the platen or table for use in securing thereto either the work itself or a fixture in which the work is clamped. Perhaps the most frequent arrangement is one in which a bolt extends upwardly from a T-slot through a hole or longitudinal slot in a clamp member one end of which rests on the work or fixture to be held and the other end of which rests on a block or stack of blocks of appropriate height.

It is an object of my invention to produce a clamp which will not require the use of the block or stack of blocks just referred to. A further object of the invention is to produce a clamp which, without modification, can be employed to clamp objects of a wide range of thicknesses to a platen or table of a machine tool. Still another object of the invention is to produce a clamp which can be employed to exert clamping pressure against a narrow ledge or shoulder on the object to be held.

In carrying out the invention I provide an elongated, preferably arched, longitudinally slotted clamp arm which may be conveniently, but not necessarily, formed of two parallel members spaced apart to provide the aforesaid slot. At one end of the clamp arm there is pivotally secured thereto a foot adapted to rest on the platen or table of the machine tool, while at the other end there is pivotally mounted a pressure member or pad adapted to rest on the work. In the preferred form of my invention, the clamp includes means for limiting outward swinging movement of the pressure member or pad to a position in which it forms, in effect, an extension of the clamp arm and is adapted to rest on a narrow ledge or shoulder of the object being clamped. The clamp arm is provided in its upper face with a series of arcuate notches each adapted to receive a cross member. A central opening in the cross member receives a clamp bolt having a head proportioned for reception in the T-slot of a machine-tool table or platen.

The accompanying drawing illustrates a preferred form of the invention: Fig. 1 is a side elevation showing the clamp in use to hold an object on the table or platen of a machine tool; Fig. 2 is a vertical section on the line 2—2 of Fig. 1; and Fig. 3 is an elevation similar to Fig. 1 showing the clamp adapted for engagement with a narrow ledge or shoulder on the object to be held.

In the device shown in the drawing, the clamp arm comprises a pair of arched side members 10 having the same general shape and disposed parallel to each other. At one end, the members 10 are pivotally connected to a foot 11 adapted to rest on the surface of a table or platen 12 of a machine tool. Conveniently, the foot 11 has a pair of spaced vertical slots in which the ends of the members 10 are respectively received, and a pivot pin 13 extends through the foot and the members 10 to provide the pivotal connection therebetween. At their opposite ends, the members 10 receive between them a pressure member or pad 14 pivotally mounted as through the medium of a cross pin 15 extending through the arms 10 and the pad.

In their upper faces, the arms 10 are provided with series of aligned arcuate notches 17 each aligned pair of which is adapted to receive the ends of a cross member 18. The surfaces of the notches 17 are circular in form as are also the notch-engaging surfaces of the cross member 18, so that the cross member can rock freely about a horizontal axis in the notches which receive it. Between the two members 10, the cross member 18 is provided with a transverse opening for the reception of a bolt 19, such bolt being provided above the cross member with a washer 20 and a nut 21. The lower end of the bolt 19 has a head 22 adapted for reception in any of the T-slots 23 in the platen or table 12.

The manner in which the clamp is used will be obvious in Fig. 1. The bolt head 22 is placed in the desired T-slot 23, the foot 11 is disposed on the table 12, and the pad 14 is seated on the object 25 which is to be clamped in place on the table 12. When the nut 21 is tightened, the members 10 are urged downwardly about the axis of the pin 13 and the pad 14 is forced firmly against the object 25. The arched shape of the members 10 adapts them to sustain the bending loads which are applied to them and is frequently of further advantage in enabling the members 10 to clear the edge portion of the object with which the pad 14 is engaged. As will readily be apparent, the clamp may be used without modification to hold objects 25 of a wide range of thicknesses. The series of notches 17 permits the cross member 18 to be placed in a plurality of positions along the members 10, thus permitting variation in the position of the clamp laterally in respect to the T-slot 23 with which it is associated. Desirably, both the bolt head 22 and the washer 20 have dimensions transverse to the bolt 19 greater than the distance between the two

members 10, whereby the bolt cannot be removed from association with the remainder of the clamp except by removal of the nut 21. As a result, all the parts of the clamp are held together when the clamp is not in use.

As will be obvious from Fig. 1, the axis of the pivot pin 15 must lie within the limits of the surface upon which the pad 14 rests, as otherwise tightening of the nut 21 would result in tipping of the pad 14 and it would be impossible to exert the desired clamping effort on the work. It is sometimes desirable, as in the situation indicated to Fig. 3, to exert the clamping effort on a ledge or shoulder 25 so narrow that the axis of the pin 15 cannot be disposed within the limits of the ledge or shoulder when the lower surface of the pad 14 engages it. To adapt the clamp for use in such a situation, I so construct it that the pad 14 can be swung outwardly into a position in which it forms, in effect, an extension of the members 10, and I provide an abutment for limiting such outward swinging movement of the pad. Conveniently, such abutment takes the form of a pin 26 extending between the two members 10 in position to engage the side of the pad 14 and limit its outward swinging movement. With the pad swung outwardly into engagement with the pin 26, it projects outwardly beyond the members 10 in a position such that its lower corner can engage and exert clamping effort against a narrow ledge or shoulder 25' on the object 25 which is to be held in position.

I claim as my invention:

A machine clamp, comprising a foot provided with two parallel spaced slots, similar clamp bars having corresponding ends received respectively

in said slots, a pivot pin extending through said foot and clamp bars to provide a pivotal interconnection, a second pivot pin extending between and interconnecting the opposite ends of the clamp bars, a pressure pad pivotally mounted on said second pin between the clamp bars, said pressure pad having no portion greater in thickness than is the space between said bars whereby it can swing bodily into such space, an abutment pin extending between said bars above said second pivot pin to engage said pressure pad and limit its outward swinging movement to a position in which it projects beyond the ends of the clamp bars and forms, in effect, an extension thereof, said clamp bars being provided in their upper faces with series of aligned, spaced, transverse notches of arcuate shape, a cross member adapted for rotatable reception in any of the aligned notches of the clamp bars, and a clamp bolt extending through said cross member and through the space between the clamp bars.

WALTER W. CARROLL.
